UNITED STATES PATENT OFFICE.

JAMES A. GIESE, OF CHICAGO, ILLINOIS, ASSIGNOR TO THE UNION BRASS MANUFACTURING COMPANY, OF SAME PLACE.

KNOB ATTACHMENT.

SPECIFICATION forming part of Letters Patent No. 254,000, dated February 21, 1882.

Application filed September 10, 1881. (Model.)

To all whom it may concern:

Be it known that I, JAMES A. GIESE, a citizen of the United States, residing at Chicago, in the county of Cook and State of Illinois, have invented certain new and useful Improvements in Latches, which are set forth in the following specification, reference being had to the accompanying drawings, in which—

Figure 1 represents a bottom plan view, partly broken away, of a door-latch embodying my improvements; Fig. 2, a section of the same, taken on the line $x-x$ of Fig. 1; Fig. 3, a detail view of the knob detached; Fig. 4, side and edge views of one of the branches of the knob-shank; Fig. 5, the wedge which holds the branches apart, and Fig. 6 the inner end of the spindle.

My invention relates to door-latches, the latches proper of which are operated by the rotary motion of knobs.

My invention consists of means for securing one of the knobs to the latch-case.

In the drawings, A represents a door-latch embodying my improvements. The fixed part b of the shank of the knob B is divided into two sections, b' b' , by a deep channel or groove. A shaft, b^2 , is inserted through the sections b' b' , crossing said channel and passing through and forming a pivot for the arms C C of said shank. The shank of the knob B, (which term "shank" includes the fixed part b and the branches of said shank, which have been described as the arms C C,) after pressing the arms together, is inserted into the latch-case D through a small opening, D^2 , such as is usual for this purpose. Thereupon the arms are spread apart by the manipulator, (the inside plate, D' , of the latch-case not being as yet secured in place,) their shoulders c resting on a circular step reamed out of the inside surface of the latch-case, though the use of the shoulders c and their special step is not indispensable. Next a wedge-shaped key, E, is dropped between the arms.

The spindle F is provided at its inner end with a collar, f , the end face of which is channelled to enable said collar to closely fit over

the wedge and over the ends of and between the arms, as shown in dotted lines in Fig. 2, the channelled collar thus acting as a key or strut to hold the arms apart, a lock to hold the wedge down in place, and a follower to insure the simultaneous rotation of the spindle F and the branching knob-shank. This collar f is adapted in depth to rest upon the inside plate of the latch-case when that is screwed on. The arms also serve as lugs to operate the talon-frame G.

The wedge E may be fastened to and form a part of the collar f . Its function in any case is that of a key or strut to hold the arms apart. As the collar f answers the same purpose, the wedge or key E is desirable only as making a longer bearing-surface to receive the wear occasioned by the slight movement back and forth of the knob-shank—an important consideration in a lock especially designed, as is this, for use on railway-carriages.

The borders of the perforation D^2 of the latch-case, through which perforation the knob is inserted into said case, serve to oppose the withdrawal of the knob-shank when its branches are held in their separated position.

By the above construction of a door-latch the cost of the apparatus is reduced, the latch-case is adapted to be taken entirely to pieces for repairs, and the shank of the pulling-knob has a seat within the case of hard metal, whereas in other latch-cases it is common to secure this knob by Babbitt metal, which in such cases forms the base against which it turns in pulling.

Having thus described my invention, what I claim as new, and desire to secure by Letters Patent, is—

The combination, with a latch-case, of the fixed part b of the knob-shank, the pivoted arms C C, and the collar f , holding the arms apart, substantially as set forth.

JAMES A. GIESE.
